CLAIM

The ornamental design for an earphone, as shown and described.

DESCRIPTION

FIG. 1 is a front perspective view of an earphone showing our new design;

FIG. 2 is a front elevational view of the design of FIG. 1;

FIG. 3 is a rear elevational view of the design of FIG. 1;

FIG. 4 is a top view of the design of FIG. 1;

FIG. 5 is a left side elevational view of the design of FIG. 1; and,

FIG. 6 is a right side elevational view of the design of FIG. 1.

The broken lines in the figures depict portions of the earphone that form no part of the claimed design.

1 Claim, 2 Drawing Sheets
